**BRACKET FOR CENTERING A CAMPER UNIT
WITHIN A TRUCK BED**

Carl G. Henson, 3063 Webster St., Eugene, Oreg. 97402

Filed May 6, 1971, Ser. No. 141,070

Term of patent 14 years

Int. Cl. D12—16

U.S. Cl. D14—6 A

FIG. 1 is a downward perspective view of a bracket for centering a camper unit within a truck bed showing my new design,

FIG. 2 is a side elevational view of the invention, and

FIG. 3 is an end elevational view taken from the right hand end of FIG. 2.

The wheel well shown in broken lines in FIG. 1 is included for illustrative purposes only.

I claim:

The ornamental design for a bracket for centering a camper unit within a truck bed, as shown and described.
